(57) **CLAIM**

The ornamental design for a portable container for storing consumable products as shown and described.

DESCRIPTION

FIG. 1 is a front, top, right side perspective view of a portable container for storing consumable products showing the claimed design;

FIG. 2 is a front, bottom, right side perspective view thereof;

FIG. 3 is a rear, top, left side perspective view thereof;

FIG. 4 is a top view thereof;

FIG. 5 is a bottom view thereof;

FIG. 6 is a front view thereof;

FIG. 7 is a rear view thereof;

FIG. 8 is a right side view thereof; and,

FIG. 9 is a left side view thereof.

The broken lines in the drawings illustrate portions of the portable container for storing consumable products that form no part of the claimed design.

The dot-dash-dot lines in the drawings illustrate boundaries of the portable container for storing consumable products that form no part of the claimed design.

1 Claim, 9 Drawing Sheets
